FLUID PRESSURE PRODUCING DEVICE

Ralph R. Gunderson, Detroit, Mich.

Application September 28, 1942, Serial No. 460,005

6 Claims. (Cl. 60—54.6)

The invention relates to fluid pressure producing devices and refers more particularly to devices of that type for discharging a large volume of fluid under low pressure during the first stage and then discharging a small volume of fluid under high pressure during the second stage.

The invention has for one of its objects to provide an improved fluid pressure producing device having a low pressure producing device and a high pressure producing device and so constructed that the devices operate separately and successively.

The invention has for another object to provide a fluid pressure producing device in which the low pressure and high pressure producing devices are adapted to communicate with a common outlet through separate independent passages.

The invention has for a further object to provide a fluid pressure producing device having low pressure and high pressure producing devices opposed and formed of a cylinder member having low pressure and high pressure cylinders, low pressure and high pressure pistons slideable within the cylinders, and valve mechanism controlling the separate passages between the cylinders and the common outlet and operable to trap the fluid either in one or the other of the cylinders to thereby hold the cylinder member from endwise movement with respect to the one or the other of the pistons.

The invention has for other objects to provide an improved construction of valve mechanism for controlling the passages and to provide the valve mechanism with a valve which is operable only during the return of the parts to their off position to permit the flow of fluid from the low pressure cylinder to the high pressure cylinder.

With these as well as other objects in view, the invention resides in the novel features of construction and combinations and arrangements of parts, as more fully hereinafter set forth.

In the drawing:

Figure 1 is a vertical central section through a fluid pressure producing device embodying the invention;

Figure 2 is a cross section on the line 2—2 of Figure 1;

Figure 3 is an enlarged view of a portion of Figure 1 showing the parts in different position.

The fluid pressure producing device embodying the invention is designed particularly for use in applying the brakes of a motor vehicle through

wheel cylinders connected to the outlet of the device, although it is apparent that the device may be otherwise used as, for example, in applying a brake of an airplane landing wheel through a wheel cylinder.

As shown in the drawing, the fluid pressure producing device comprises the cylinder member 1 having intermediate its ends an outlet formed of the outlet chamber 2 and the outlet port 3, which latter is adapted to be connected to the fluid line leading to either one or more wheel cylinders for operating one or more brakes. The cylinder member has at opposite sides of the outlet the axially aligned low pressure cylinder 4 and high pressure cylinder 5, the former having an internal diameter larger than the internal diameter of the latter. The cylinder member also has separate passages 6 and 8 between the low pressure cylinder and outlet and the high pressure cylinder and outlet. The passage 6 is provided by bores extending through the plug 7 which is threaded into the portion of the intermediate partition wall 1' of the cylinder member between the inner end of the low pressure cylinder and the outlet chamber. The passage 8 is formed by a bore 9 which extends through the portion of the intermediate partition wall 1' between the inner end of the high pressure cylinder and the outlet chamber. 9 is the low pressure piston within the low pressure cylinder and 10 is the high pressure piston within the high pressure cylinder, the two pistons being relatively movable toward each other and the outlet during their working strokes.

11 and 12 are retracting coil springs respectively between the intermediate partition wall 1' and the low pressure piston 9 and the intermediate partition wall and the high pressure piston 10 for relatively retracting the pistons and cylinder member and relatively moving the same to off positions. The off position of the low pressure piston is determined by the abutment ring 13 held in place by the split ring 14 engaging an annular groove in the open end of the low pressure cylinder. The off position of the high pressure piston is determined by the pin 15 extending through and threaded into the open end of the high pressure cylinder. Suitable sealing rings are provided between the pistons and their cylinders for preventing the escape of the braking fluid, which is a liquid. 16 is the fluid reservoir above and preferably integral with the cylinder member. This reservoir is suitably vented to the atmosphere and communicates with the low pres-

sure cylinder and the high pressure cylinder in the off positions of their respective pistons through the openings 17 and 18, respectively, which are located in the portions of the cylinder walls immediately below the reservoir.

The pistons carry the cylinder member and reservoir and one of the pistons is pivotally connected to a pedal and the other pivotally connected to a support. In the event that the fluid pressure producing device is used in applying the brakes of a motor vehicle, one of the pistons is pivotally connected beyond the cylinder member to the foot pedal of the motor vehicle, while the other of the pistons is pivotally connected beyond the cylinder member to a support upon the chassis 15 of the motor vehicle.

19 is a valve mechanism constructed to compel the low pressure producing device which is formed of the low pressure cylinder and piston and the high pressure producing device which is formed of the high pressure cylinder and piston to operate separately and in sequence when actuated.

The valve mechanism normally occupies a position opening the passage 6 between the low pressure cylinder and the outlet and closing the passage 8 between the high pressure cylinder and the outlet. As a result, when the pedal is depressed to actuate the fluid pressure producing device, fluid is trapped in the high pressure cylinder during the first stage and the high pressure piston acts on the fluid trapped in the high pressure cylinder to hold the cylinder member from endwise movement relative to the high pressure piston and to compel the low pressure cylinder to advance relative to the low pressure piston to force the fluid directly to the outlet and then to one or more wheel cylinders for applying one or more brakes. When the pressure developed within the high pressure cylinder becomes sufficient, the valve mechanism is moved to positions successively closing the passage 6 and opening the passage 8 so that upon continued actuation of the fluid pressure producing device fluid is trapped in the low pressure cylinder and the low pressure piston acts on the fluid trapped in the low pressure cylinder to hold the cylinder member from endwise movement relative to the low pressure piston and to compel the high pressure piston to advance within the high pressure cylinder to force the liquid directly to the outlet and then to the one or more wheel cylinders for applying the one or more brakes under a higher pressure than that during the first stage. It will be noted that the pressure of the fluid trapped in the high pressure cylinder is much greater than that of the fluid being forced from the low pressure cylinder because of the difference in internal diameters of the two cylinders. Pressure of the fluid discharged from the low pressure cylinder during the first stage is preferably that required to take up brake clearance, while the pressure of fluid discharged from the high pressure cylinder during the second stage is sufficient to very readily apply the brake with the desired force.

The valve mechanism 19 comprises the valve 20 having a head slidable within an enlarged portion of the passage 8 and a stem slidable within the bore 21 extending axially of the plug 7. The head is preferably provided with a suitable sealing ring engageable with the wall of the enlarged portion of the passage. The valve 20 is normally held in a position closing the passage 8 by the coil spring 22 between the bottom 23 of the plug 7 and the end of the valve stem, this spring normally holding the head against the shoulder

24 formed by the reduced portion of the passage 8. The valve mechanism also comprises the second valve 25 which is in the nature of a rubber disc sleeved upon the stem of the valve 20 and adapted to be moved to a position to close the passage 6. 26 is a suitable collar also sleeved on the stem of the valve 20 and engageable in the recess 27 formed in the plug 7 at the ends of the bores forming the passage 6 to prevent the valve from being forced into the bores. The collar 26 is engageable with the annular shoulder 28 formed on the stem of the valve 20 to limit the movement of the valve 25 toward the passage 6. The collar is normally held in engagement with the shoulder by the coil spring 29 encircling the stem of the valve 20 and abutting the valve 25 and the head of the valve 20, the spring permitting movement of the valve 25 relative to the valve 20 after the valve 25 has closed the passage 6 and during continued movement of the valve 20 to open position.

With the construction as thus far described, it will be seen that with the parts in their off positions, as shown in Figure 1, upon actuation of the fluid pressure producing device the low pressure piston 9 and the high pressure piston 10 will be relatively moved toward each other until the high pressure piston closes the port 18, at which time the fluid within the high pressure cylinder is trapped by the valve 20. As a result, the cylinder member 1 is held from endwise movement relative to the high pressure piston 10 so that upon continued actuation the cylinder member 1 is advanced relative to the low pressure piston 9 to force fluid through the passage 6, the outlet chamber 2 and the outlet port 3 to the one or more wheel cylinders to apply the one or more brakes. When all braking clearance is taken up, the pressure of the fluid built up within the high pressure cylinder is such that the fluid exerts a force upon the valve 20 which is greater than the strength of the spring 22 so that the fluid in the high pressure cylinder acts upon the valve 20 to move the same toward the outlet. During the first portion of the movement of this valve the valve 25 closes the passage 6 between the low pressure cylinder and the outlet so that fluid is trapped in the low pressure cylinder and the low pressure piston acts to hold the cylinder member 1 from endwise movement relative to the low pressure piston and the high pressure piston is advanced on its working stroke to move the valve 20 to a position opening the passage 8 and to force the fluid to the outlet and then to the one or more wheel cylinders to complete the application of the one or more brakes.

To relieve the low pressure cylinder during the relative retraction of the cylinder member and the low pressure piston to the off position of the low pressure piston, the low pressure piston is formed with the annular channel 30 which remains at all times in communication with the port 31 in the low pressure cylinder wall communicating with the reservoir. The low pressure piston is also formed with the transverse port 32 in its head and carries the valve 33 located at the working or pressure side of its head and normally held in engagement with this side by the coil spring 34. During the relative retraction of the cylinder member and the low pressure piston, this valve is moved to open position so that fluid may flow from the reservoir through the port 31, the channel 30 and the port 32 into the portion of the low pressure cylinder in advance of the low pressure piston. To relieve the high pressure cylinder dur-

ing the retraction of the high pressure piston, the valve 20 is formed with the axial bore 35 extending therethrough and the bottom of the plug 7 is formed with the axial port 36. 37 is a valve carried by the valve 20 and located at the end of the latter exposed to the high pressure cylinder. This valve is normally held closed by the coil spring 38 which abuts an annular shoulder formed in the bore 35 and the head 39 secured to the end of the valve rod 40. During the movement of the cylinder member relative to the low pressure piston, the pressure built up in the high pressure cylinder increases at a much greater rate than the pressure in the low pressure cylinder because of their difference in diameters so that the fluid in the high pressure cylinder serves to easily hold the valve 37 closed during the first stage of operation. It will be seen that during the retraction of the high pressure piston the valve 35 is moved to open position to allow fluid to flow from the low pressure cylinder into the high pressure cylinder. When the pistons are in their off positions, the compensating ports 17 and 18 are open and allow any excess fluid in the cylinders to return to the reservoir.

It will thus be seen that I have provided an improved construction of fluid pressure producing device which acts in two successive stages, during the first of which a large volume of fluid under low pressure is discharged and during the second of which a small volume of fluid under high pressure is discharged. It will also be seen that the structure is such that the low pressure and high pressure producing devices operate separately and successively and discharge fluid to a common outlet through separate and independent passages. It will be further seen that I have provided an improved construction of valve mechanism which is operable to trap the fluid either in the low pressure producing device or in the high pressure producing device.

What I claim as my invention is:

1. A fluid pressure producing device comprising a cylinder member having cylinders of different diameters, an outlet and passages directly between said cylinders and outlet, pistons within said cylinders, and valve mechanism controlling said passages, said valve mechanism being movable by the liquid under a pressure developed in the cylinder of smaller diameter and comprising a valve in the passage between the cylinder of smaller diameter and said outlet, and a second valve movable by said first mentioned valve to close the passage between the cylinder of larger diameter and said outlet prior to opening of said first mentioned valve, and means for normally maintaining said first mentioned valve in closed position and said second valve in open position.

2. A fluid pressure producing device comprising a cylinder member having cylinders of different diameters, an outlet and passages directly between said cylinders and outlet, pistons within said cylinders, and valve mechanism controlling said passages, said valve mechanism normally occupying a position opening the passage between the cylinder of larger diameter and said outlet and closing the passage between the cylinder of smaller diameter and said outlet, said valve mechanism being automatically movable by the fluid under a pressure developed in the cylinder of smaller diameter to a position closing the passage

between the cylinder of larger diameter and said outlet and subsequently opening the passage between the cylinder of smaller diameter and said outlet.

5 3. A fluid pressure producing device comprising a cylinder member having an outlet, a low pressure cylinder at one side of said outlet, a high pressure cylinder at the opposite side of said outlet, and separate passages between said cylinders and outlet, pistons within said cylinders and relatively movable toward each other during their pressure stroke, and valve mechanism controlling said passages, said valve mechanism being movable by the fluid under a pressure developed in said high pressure cylinder and serving to successively trap fluid in said high pressure cylinder and low pressure cylinder and at the same time occupy positions successively opening the passages between said low pressure cylinder and outlet and high pressure cylinder and outlet, said valve mechanism comprising a different valve from each passage with one valve movable by another valve and closing its passage prior to the other valve opening its passage.

25 4. A fluid pressure producing device comprising a cylinder member having substantially axially aligned low pressure and high pressure cylinders, an outlet between said cylinders and independent passages connecting said cylinders and outlet, pistons within said cylinders, and valve mechanism controlling said passages, said valve mechanism being movable by the fluid under a pressure developed in said high pressure cylinder and comprising a valve in the passage connecting said high pressure cylinder and said outlet, a spring for resiliently holding said valve in a position closing the last mentioned passage, a second valve carried by said first mentioned valve and movable upon movement of said first mentioned valve to close the passage extending between said low pressure cylinder and said outlet, and a spring between said valves for resiliently holding said second valve in a position to close its passage.

40 5. A fluid pressure producing device comprising a floating cylinder member having an outlet and cylinders of different diameters at opposite sides of and adapted to communicate with said outlet, opposed pistons within said cylinders and carrying said cylinder member, and means movable by the fluid under a pressure developed in one of said cylinders for controlling the communication between said cylinders and outlet operable to trap fluid in either of said cylinders and to place either of said cylinders in communication with said outlet, said controlling means being operable to trap fluid in one of said cylinders before placing the other of said cylinders in communication with said outlet.

60 6. A fluid pressure producing device comprising a cylinder member having an outlet, cylinders of different diameters at opposite sides of said outlet and separate passages between said cylinders and outlet, pistons within said cylinders and opposed to each other, and valve mechanism movable by fluid under a pressure developed in one of said cylinders and comprising a different valve for each passage, one of said valves being movable by another valve and closing its passage prior to the other valve opening its passage.
